UNITED STATES PATENT OFFICE.

KISTEL OSEL, OF ST. PAUL, MINNESOTA.

GRAIN-DOOR FOR RAILWAY-CARS.

SPECIFICATION forming part of Letters Patent No. 790,521, dated May 23, 1905.

Application filed July 18, 1904. Serial No. 216,926.

To all whom it may concern:

Be it known that I, KISTEL OSEL, a citizen of the United States, residing at St. Paul, in the county of Ramsey and State of Minnesota, 5 have invented certain new and useful Improvements in Grain-Doors for Railway-Cars, of which the following is a specification.

My invention relates to improvements in grain-doors for railway-cars; and it consists 10 particularly in improvements in the sliding supports for the door and the means for locking the door in raised and in lowered positions.

To this end my invention consists in the features of construction and combination hereinafter particularly described and claimed.

In the accompanying drawings, forming part of this specification, Figure 1 represents a view of the door as seen from the outside 20 of the car. Fig. 2 is a view as seen from the inside of the car. Fig. 3 is a vertical section on line *xx* of Fig. 2 with the door in lowered position. Fig. 4 is a similar view with the door in raised position. Fig. 5 is a section on line *yy* of Fig. 3. Fig. 6 is a section on line *zz* of Fig. 3. Figs. 7 to 9, inclusive, are detail views of a portion of the supports for the door; and Fig. 10 is a detailed view of a catch for holding the door in lowered position.

In the drawings, A represents a grain-door of known construction, provided at the top with a hinged flap 2. The flap 2 is preferably wider than the door, so that when in closed position it will extend across the posts, against which it is held by means of the U-shaped catches 4, loosely and pivotally secured to the sides of the posts by staples 5. As indicated by the dotted lines in Fig. 4, the 35 catches may be turned laterally, as it is evident will be necessary, in order to bring the jaws 6 and 7 of the catches over the upper edge of the flap.

Upon the face of each post is a guide 8, consisting of a strip of metal secured to the post by screws 9. Along each side of the strip extends a recess 10. The recesses 10 at the upper end of the slide are separated by a rib 11, integrally formed with the under side of 45 the slide and at the lower end of the slide are separated by a rib 12, carried by the post and

forming a continuation of the rib 11. At the top the guide is turned upon the arc of a circle to the inner face of the post, where it is suitably secured. Upon the door are secured 55 the brackets B by means of bolts 14, each bracket being turned at a right angle with the door, as shown in Fig. 5. Loosely pivoted through the outturned end of each bracket 13 by a spindle 16 is a slide 15, having inturned 60 flanges 17, which embrace the edges of the corresponding guide 8 and fit within the recesses 10. The slide 15 thus turns freely upon the spindle 14. Each guide 8 is formed at its top with a notch 18, long enough to receive 65 within it one of the slides 15. The flanges 17 are of greater length than the body of the slide, so that when the door is in raised position the ends 19 of one flange will bear against the guide upon opposite sides of the 70 notch 18 and the ends of the other flange will bear against the lower sides of the curved portion of the guide to prevent disconnection. In order to allow the slides to pass freely around the curved upper ends of the 75 guides, I preferably cut away the corners of the slides, as shown in Fig. 7.

In order to hold the door in raised position, I provide suitable depending hooks 20, having pivotal support from the upper beams of 80 the car.

In operation the flap 2 is first turned back upon its hinges and the door then raised, the slides traveling upward upon the guides 8. The slides being freely pivoted will follow 85 the guides around the curve at the top until the notches are reached, when they will drop by gravity into the notches, thus holding the door in raised position. The door may then be swung back upon the pivots 16, as shown 90 in Fig. 4, and secured in raised position by the hooks 20. As shown in Fig. 4, this brings the hinged end of the door so close to the plate 21 of the car that the door cannot be moved to carry the slides out of the notches 95 until it has first been swung downward. Accidental sliding downward of the door upon the guides is thus prevented.

Having now described my invention, what I claim as new, and desire to secure by Letters 100 Patent, is—

1. The combination with a car formed with

- the door-posts, of a grain-door, a pair of vertical guides secured on the opposing faces of the door-posts and having inwardly-turned upper ends, the inwardly-turned upper end 5 of each guide being formed with a notch in its upper side, and slides hinged to said door and formed with flanges embracing said guides, said slides being proportioned to drop into said notches when the door is raised.
- 10 2. The combination with a car formed with the door-posts, of a car-door therefor, a pair of vertical guides secured on the opposing faces of the door-posts and having inwardly-turned upper ends, right-angled brackets secured 15 to the outer face of the door, slides loosely pivoted to the outwardly-projecting ends of said brackets, said slides being formed with flanges embracing the edges of said guides, and means for interlocking said slides 20 and the inwardly-turned ends of said guides when the door is raised.
3. The combination with a car formed with a door-frame, of a grain-door, a pair of vertical guides secured in the sides of the door- 25 frame, and having inwardly-turned upper ends, the upper end of each guide being formed with a notch in its upper side, slides hinged to said door-frame with flanges embracing said guides, said slides fitting in said notches 30 when the door is raised and said flanges being of greater length than the body of the slide, for the purpose set forth.
4. The combination with a car formed with

a door-frame, of a grain-door, a pair of vertical guides secured in the sides of the door-frame and having their upper ends turned inwardly upon the arc of a circle, said inwardly-turned ends being each provided in its upper edge with a notch, slides hinged to said door and formed with flanges embracing said 35 guides, said slides fitting in said notches when the door is in raised position, and said flanges being of greater length than the body of the slide, and downwardly-extending hooks for holding said door in raised position.

5. The combination with a car formed with a door-frame, of a grain-door, a pair of vertical guides secured in the sides of the door-frame and having their upper ends turned inwardly upon the arc of a circle, said inwardly- 40 turned ends being each provided in its upper edge with a notch, right-angled brackets secured to the outer face of said door, slides loosely pivoted in the outwardly-turned ends of said bracket, inwardly-turned flanges carried by said slides for embracing said guides, said flanges being of greater length than the body of said slide, and said slides being proportioned to fit into said notches when the 45 door is raised.

In testimony whereof I affix my signature in presence of two witnesses.

KISTEL OSEL.
